UNITED STATES PATENT OFFICE.

LYMAN P. FRENCH, OF BOSTON, MASSACHUSETTS.

FURNACE.

SPECIFICATION forming part of Letters Patent No. 299,974, dated June 10, 1884.

Application filed October 26, 1883. (No model.)

To all whom it may concern:

Be it known that I, LYMAN P. FRENCH, of Boston, county of Suffolk, State of Massachusetts, have invented an Improvement in Furnaces, of which the following description, in connection with the accompanying drawings, is a specification, like letters on the drawings representing like parts.

My invention relating to furnaces is shown embodied in a locomotive fire-box or furnace having an inclined bridge-wall extending diagonally across the fire-box from its lower front end toward its rear upper end, the furnace also having a deflecting-wall depending from its crown-sheet in front of the upper edge of the bridge-wall.

In another application for Letters Patent No. 95,125, filed May 16, 1883, I have shown and described a furnace having walls of this general arrangement, the bridge-wall, however, being partly composed of a water-space or table which is necessarily a permanent part of the fire-box, and is very expensive.

The present invention consists in a novel construction of the bridge-wall, which is of masonry, and is made hollow for the introduction of heated air.

Masonry walls for the introduction of air have usually been made of hollow bricks provided with numerous small perforations for the air to flow through; but such construction is very objectionable, as owing to the great difference in temperature of the different parts of the bricks they expand unequally and soon break or crumble, and furthermore the area of heating-surface to which the air is exposed is reduced by the perforations.

Arches or walls for the introduction of air have also been made of fire-brick having a single large air passage or chamber within them, and of two layers of brick having corresponding grooves in their adjacent faces which constitute a series of tubular passages passing longitudinally through the wall. In this latter construction the main part of the two layers are in contact with one another, forming a solid mass of masonry. When the wall has a large space or chamber included within it, and the faces of the brick inclosing the said space are separated from one another and unequally exposed to the fire, as is usually the case, one

side, for example, being exposed directly to the fire, and the other protected therefrom by the intervening layer of air, the said faces of the brick will be unequally heated and the greater expansion of the one than of the other will produce severe internal strains, which will soon result in the destruction of the brick and arch constructed therefrom. These objections are obviated in the present invention by making the wall of two independent layers of bricks separated a sufficient distance to inclose between them an air space or chamber of the desired size, the said chamber opening at the end of the wall directly into the fire-box. The separation of the layers is preferably effected by providing them with laterally-projecting flanges, which are turned upward in the lower layer and downward in the upper layer, the latter lying on the former. Each layer being quite thin but of uniform thickness throughout, will attain substantially uniform temperature throughout, and the two layers being disconnected from one another, the one next the fire, which will reach the highest temperature, is free to expand or crawl along the other without producing any strain, so that a wall or arch constructed in this manner is very durable.

Figure 1 is a longitudinal section of a locomotive fire-box embodying this invention. Fig. 2 is a horizontal section thereof on line *x*; Fig. 3, a perspective view of one of the bricks of which the arch or bridge-wall is composed.

The fire-box *a*, grate *b*, and opening *c*, for the introduction of fuel, are all of usual construction, being as found in locomotives now in use. The said fire-box contains an arch or bridge-wall, *e e'*, composed of two independent layers of fire-brick, shown in this instance as supported on water-pipes *i*, connected by suitable couplings with the sheets of the fire-box. The lower layer, *e*, of brick rests directly on the said pipes, and the upper layer, *e'*, is supported a short distance above the lower layer, thus inclosing an air space or chamber between them, provided with inlet-passages *m* through the walls of the fire-box connecting with the external atmosphere and admitting air to the spaces between the two parts of the bridge-wall. As herein shown, the up-

per portion of the bridge-wall is supported above the lower portion, e , by means of corresponding flanges, e^2 , on the two layers of brick, and the upper edge of the air-chamber in the 5 bridge-wall is left open, as shown, permitting the air to pass from it directly into the fire-box.

The arrangement of the fire-box is substantially the same as described in my former application, the bridge-wall extending from the lower front portion of the fire-box below the flues, diagonally across the fire-box in a rearward and upward direction to a point a short distance below the crown-sheet, and the fire- 10 box is also provided with a deflecting-wall, m' , extending from the crown-sheet forward and downward toward the bridge-wall, the lower edge of the said deflecting-wall being in front of and below the level of the upper edge of the bridge-wall. In the said application, 15 however, the bridge-wall was shown as having an extension reaching the rear sheet above the door, so that the products of combustion were compelled to pass through two passages, 20 one at either side of the door. The said extension was intended to protect the flues from access of cold air when the door was opened for the introduction of fuel, and the claims of the said application cover, broadly, the combination of the bridge-wall and deflecting-wall 25 having the described arrangement with relation to one another, independently of the extension over the door. It is often found to be more advantageous to afford a uniform passage 30 for the products of combustion over the entire upper edge of the bridge-wall than to provide for the protection of the flues when the door is opened, and in the present application the upper edge of bridge-wall is substantially 35 parallel with the crown-sheet, thereby affording a uniform passage for the products of combustion over the entire upper edge.

I do not in the present application broadly 40 claim the combination of the bridge-wall and deflecting-wall, nor a bridge-wall provided with an air-chamber.

I claim—

1. In a furnace, a bridge-wall or arch composed of two independent thin layers of unper-

forated fire-brick, each layer being of substantially uniform thickness throughout, and the layers being separated from between them, the said chamber communicating with the air outside of the furnace and opening at one end 55 of the layers of brick into the furnace, substantially as described.

2. The bridge-wall inclined from the lower front wall of the fire-box rearwardly and upwardly, the said wall being composed of two 60 independent layers of bricks, each layer being of substantially uniform thickness, and the two layers being separated by an air-space, which opens into the furnace at the upper edge of the wall and communicates with the 65 air external to the furnace at the lower portion of the said wall, substantially as described.

3. The bridge-wall inclined from the lower front wall of the fire-box rearwardly and upwardly, the said wall being composed of two 70 layers of bricks separated by an air-space which opens into the furnace at the upper edge of the wall and communicates with the air at the outside of the furnace at the lower portion of the said wall, combined with the 75 deflecting-wall depending from the crown-sheet in front of the upper edge of the said bridge-wall, the lower edge of the said deflecting-wall being below the level of the upper edge of the said bridge-wall, substantially as 80 described.

4. The bridge-wall extending from the lower front portion of the fire-box below the flues rearwardly and upwardly toward the crown-sheet, the upper edge of the said wall being 85 substantially parallel with the crown-sheet, combined with the deflecting-wall, depending from the crown-sheet in an inclined forward and downward direction, and having its lower edge parallel with and below the level of the 90 upper edge of the bridge-wall, substantially as described.

In testimony whereof I have signed my name to this specification in the presence of two subscribing witnesses.

LYMAN P. FRENCH.
